TELEPHONE SYSTEM.

Application filed December 28, 1927. Serial No. 243,059.

This invention relates to telephone systems and particularly to circuit arrangements associated with long distance transmission lines at a central office.

- 5 In general practice, a long distance transmission line may be associated with a plurality of different switchboards and positions at a central office. It may be found desirable, such as at night, when a decrease 10 in traffic may warrant a decrease in the operating force at a central office, to have both incoming and outgoing calls over the long distance lines handled at positions on a board which would normally be used for 15 only one type of call. In instances when a call is received at an incoming board which requires the attention of a through operator, such as an operator at an outgoing board, it is desirable to transfer such a call to an outgoing board.

Heretofore such systems have been devised and satisfied the requirements imposed by traffic conditions, but the volume of toll traffic has increased to such an extent as to 25 necessitate toll boards of increased size which results in correspondingly increased demands upon the switchboard circuits.

It is the object of this invention to improve the equipment located at toll switchboards in such a manner as to satisfy the increased demands made upon toll line equipment.

This object is attained in accordance with a feature of the invention by the provision 35 of a toll line circuit provided with transfer equipment which permits the transfer of calls between boards in a central office.

Another feature of the invention resides in a circuit arrangement whereby a call at 40 one board may not be transferred to another board at which no signals to indicate the transfer are available. This feature is particularly applicable to large toll offices wherein it is found desirable to provide only 45 a certain percentage of toll lines available at that office, with transfer facilities. For the sake of uniformity in construction and assembly, each board is provided with a certain number of transfer keys, which number usually does not correspond to the number 50 of lines that have transfer facilities, so that the accidental actuation of a key corresponding to such a line would ordinarily cause the transfer of a call without the

transmission of a signal and would render 55 the call lost and the particular toll line inaccessible to further calls until the transfer relays associated therewith were restored. The present feature does not permit the transfer circuit to function unless there is an 60 operative signal associated therewith.

Generally stated, the invention contemplates the use of a transfer circuit wherein the relay which effects the signal transfer first operates in series with the signal to be 65 actuated and upon operating, locks up independent of the signal and causes the signal to be actuated in a circuit free of all other equipment.

The invention may now be more fully 70 understood from the following detailed description made with reference to the accompanying drawing which illustrates a circuit diagram of the invention in its preferred form.

The toll line L is shown terminating in an exchange at a plurality of positions, A, B, C and D. The positions A and D indicate respectively the service observing position and the inward position, whereas B and C represent through positions located at different switchboards. It will now be assumed that the toll line L has been seized at a distant office in the establishment of a connection and that signaling current has been applied to the line 85 in any well-known manner. Relay 10 being normally bridged across the tip and ring conductors of the line circuit L, responds to the signaling current incoming over the line and in attracting its armature causes relay 90 11 to operate in a circuit extending from grounded battery, outer left-hand armature and back contact of relay 12, winding of relay 11, front contact and armature of relay 10 to ground.

Relay 11 upon operating causes relay 13 to operate by way of its right-hand winding. Relay 13 in attracting its outermost armature causes the drops 14, 15, 16 and 17 and all multiply drops associated with the line L, to be actuated over an obvious circuit to serve as busy signals at the positions at which these drops are located. At its middle armature relay 13 locks in an obvious circuit under the control of relay 12. At its innermost armature relay 13 completes a circuit extending from grounded battery, outer left-hand armature and back

contact of relay 12, middle armature and front contact of relay 13, front contact and innermost armature of relay 13, inner left-hand armature and back contact of relay 18, through the filaments of lamps 19 and 22 at the service observing position A and the inward position D respectively to ground.

Lamps 19 and 22 are lighted in this circuit and indicate to the operators located at 10 the positions at which these lamps are situated that a call is awaiting attention on the toll line L. According to general practice the operator at the inward position D upon noting the illumination of lamp 22 answers 15 the call by inserting plug 23 of the answering end of the cord circuit E into jack 24 associated with the lighted line lamp 22. The operator at the service observing position may plug into the connection by way 20 of the jack 35 at position A in order to observe the progress of the call.

Upon the insertion of plug 23 into jack 24 relay 12 operates in a circuit extending from grounded battery, resistance element 25 33, sleeve contacts of plug 23, and jack 24, back contact and outer left-hand armature of relay 18 to ground through the winding of relay 12. Relay 12 attracting its right-hand armature, removes the ringing relay 30 10 from across the tip and ring conductors of the line circuit L, thereby improving transmission. In attracting its outer left-hand armature relay 12 opens the locking circuit for relay 13, which relay thereupon releases, extinguishing the line lamps 19 and 35 22 at positions A and B. At its inner left-hand armature and front contact relay 12 supplies battery to the busy signals 14, 15, 16 and 17 to maintain them actuated after 40 the release of relay 13.

Should the nature of the incoming call be such as to require the attention of a through operator, the operator at the inward position D proceeds to transfer the call to a through operator by momentarily actuating the transfer key 25.

Relays 13 and 18 now operate in a circuit extending from grounded battery, right-hand winding of relay 13, left-hand winding 50 of relay 18, to ground by way of the alternate contacts of key 25. In attracting its outer left-hand armature relay 18 opens the circuit for relay 12, whereupon the operation of relay 13 performs the same functions 55 as hereinbefore described in connection with its initial operation with the exception of the lighting of lamp 19. At its inner left-hand armature relay 18 opens the circuit to the lamps 19 and 22, and also closes a circuit 60 for relay 26 extending from grounded battery, outer left-hand armature and back contact of relay 12, winding of relay 26, back contact and left-hand armature of relay 26, right-hand armature and front contact of 65 relay 18, to ground through the filament of

lamp 20 at the through position B. Lamp 20 at position B and similar lamps at other through position do not light in this circuit owing to the inclusion of the winding of relay 26 therein. However, relay 26 operates and in attracting its left-hand armature causes the lamps such as 20 at the through positions to be lighted in a circuit exclusive of any relay winding such as that of 26. Relay 26 now locks in series with the 70 right-hand winding of relay 18. This locking circuit may be traced from grounded battery, outer left-hand armature and back contact of relay 12, winding of relay 26, closed contacts 27 of relay 26, right-hand 75 winding of relay 18, to ground. At its right-hand armature, relay 26 causes lamp 21 at the through position C to be lighted. An operator at any of the through positions may proceed to handle the call by inserting the 80 plug of an answering cord into a jack such as 28 or 29, whereupon relay 30 is caused to operate over the sleeve circuit. Relay 30 at its two outer armatures, disassociates the 85 jack 24 at the inward position D, and all 90 other corresponding jacks from the line circuit, removing all surplus cable from the connection and preventing disturbances caused by operators plugging into these multiple jacks, thereby affording better transmission on through connections. At its inner 95 upper armature relay 30 connects battery to the winding of relay 12 through resistance 31 to cause this relay to operate and perform the same functions hereinbefore described in 100 connection with its operation when the incoming call was answered by the operator at the inward position D.

From the foregoing description of the transfer operation it is evident that there 105 is no possibility of losing a call upon the accidental actuation of a transfer key on a line which is not provided with signal lamps at the through positions, since neither relay 18 nor 26 can lock up if the lamps such as 110 20 are not present or in an operative condition. It also appears that the number of 115 multiple lamps at the through positions which may be lighted is not limited since the lamps are lighted in a circuit independent of any other equipment. Furthermore, other armatures and contacts may be added to the structure of relay 26 which armatures may control lamps at other through positions in a manner similar to that in which lamp 21 120 is controlled.

What is claimed is:

1. In a telephone exchange system, a transmission line terminating in a plurality of sets of switching terminals, a signal at 125 each of said sets of terminals, means responsive to a call incoming on said transmission line for operating one of said signals, a relay, and means for effecting the operation of said relay in series with another of said 130

signals and thereafter maintaining said relay and said second signal operated in separate circuits.

2. In a telephone exchange system, a transmission line terminating in a plurality of sets of switching terminals, a signal at each of said sets of terminals, means responsive to a call incoming on said transmission line for operating one of said signals, a relay, and manually controlled means for effecting the operation of said relay in series with another of said signals and thereafter maintaining said relay and said second signal operated in separate circuits.
3. In a telephone system, a line terminating at a plurality of positions, a signal at each of said positions, means responsive to a call incoming over said line for actuating the signal at one of said positions, and a relay adapted, upon operation, to substitute a signal at another position for said first mentioned signal, the operation of said relay depending upon the receptive condition of the signal at said second mentioned position.
4. In a telephone system, a line terminating at a plurality of positions, a signal at each of said positions, means responsive to a call incoming over said line for actuating the signal at one of said positions, a transfer relay, a key, and means controlled by said key for connecting said transfer relay in a series circuit with a signal at another position, said relay, upon operating, adapted to operate said second signal in a circuit independent of said relay.
5. In a telephone system, a line terminating at a plurality of positions, a signal at each of said positions, means responsive to a call incoming over said line for actuating the signal at one of said positions, a transfer relay, a key, and means controlled by said key for connecting said transfer relay in a series circuit with a signal at another position, said relay, upon operating, adapted to lock in a circuit independent of said second signal.

6. In a telephone system, a line terminating at a plurality of positions, a signal at each of said positions, means responsive to a call incoming over said line for actuating the signal at one of said positions, a transfer relay, a key, and means controlled by said key for connecting said transfer relay in a series circuit with a signal at another position, said relay, upon operating, adapted to lock in a circuit independent of said second signal and maintain said second signal operated. 50 55

7. In a telephone system, a line circuit terminating at a plurality of positions, a signal at each of said positions, means responsive to a call incoming over said line for actuating one of said signals, a relay, a second relay, manually operated means for actuating said first relay to disable said signal and connect another of said signals in series with said second relay whereupon said second relay operates and disassociates its winding from the circuit of said second signal. 60 65 70

8. In a signal transfer circuit, a signal, a relay, a second relay, and means for actuating said first relay to cause said signal and said second relay to be connected in a series circuit and said second relay to be operated whereupon said second relay locks in a circuit independent of said signal. 75

9. In a signal transfer circuit, a signal, a relay, a second relay, and means for actuating said first relay to cause said signal and said second relay to be connected in a series circuit and said second relay to be operated whereupon said second relay locks in series with said first relay in a circuit independent of said signal. 80 85

In witness whereof, we hereunto subscribe our names this 27th day of December, A. D. 1927.

JOHN F. TOOMEY.
